DESIGN FOR A COMBINED CIGARETTE EXTINGUISHER AND ASH RECEIVER

Michael M. Circelli, Pittsburgh, Pa.

Application June 20, 1940, Serial No. 93,134

Term of patent 3½ years

To all whom it may concern:

Be it known that I, Michael M. Circelli, a citizen of the United States, residing at Pittsburgh, in the county of Allegheny and State of Pennsylvania, have invented a new, original, and ornamental Design for a Combined Cigarette Extinguisher and Ash Receiver, of which the following is a specification, reference being had to the accompanying drawing, forming a part thereof.

The figure is a perspective view of a combined cigarette extinguisher and ash receiver, showing my new design.

I claim:

The ornamental design for a combined cigarette extinguisher and ash receiver, as shown.

MICHAEL M. CIRCELLI.
